Primary Examiner — W. A. Teddy Falloway*(74) Attorney, Agent, or Firm* — Bereskin & Parr LLP/S.E.N.C.R.L. s.r.l.(57) **CLAIM**

The ornamental design for an assembly of food containers, as shown and described.

DESCRIPTION

FIG. 1 is a perspective view of an assembly of food containers;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in FIGS. 1 to 6 illustrate portions of the assembly of food containers that form no part of the claimed design.

1 Claim, 5 Drawing Sheets(56)
